ADJUSTABLE OVERHEAD DOOR HINGE

Roscoe Fowler, Los Angeles, Calif.

Application November 14, 1949, Serial No. 127,035

3 Claims. (Cl. 16—129)

1

My invention relates to overhead doors, for garages, and the like.

One of the principal objects of this invention is to provide improvements over the overhead door construction disclosed in patent application, Serial No. 641,110, particularly in providing, what is termed, "hardware" for an overhead door, which hardware is very simple and economical of construction, durable, and which will not readily get out of order.

Another important object of this invention is to provide overhead door supporting and operating means which consists of a minimum number of parts, and yet one which is adjustable in various respects to doors of different sizes and weights.

A further important object of this invention is to provide overhead garage door hardware having simple and economical means for adjusting the tension and action of the door counterbalance spring means, and means of this class which may be easily and quickly adjusted.

With these and other objects in view, as will appear hereinafter, I have devised an overhead door having certain novel features of construction, combination, and arrangement of parts and portions, as will be hereinafter described in detail, and particularly set forth in the appended claims, reference being had to the accompanying drawings and to the characters of reference thereon, which form a part of this application, in which:

Fig. 1 is a sectional elevational view through a door and door frame or jamb therefor, showing the door hardware or door supporting and operating mechanism at one side of the door, the door being shown in closed position;

Fig. 2 is a similar view thereof through the door and frame, but showing the former in partly open position, and showing by dotted lines the door and the supporting and operating mechanism in full open position; and,

Fig. 3 is a fragmentary elevational view, taken from the inside of the door, as indicated by 3—3 of Fig. 1.

The door or closure member, designated 1, is of conventional construction and may be of any desired size. It is arranged to be closed over the opening 2^a of the frame or jamb 2. As shown, the frame has a stop 2^b at the upper portion of the opening to limit the outward or closed position of the upper end of the door or closure member.

At each side of the frame is mounted a duplicate arm and lever mechanism, shown best in

2

Figs. 1 and 2. Since the mechanisms are duplicates, only one will be described.

The whole mechanism is supported on the inner side of a side member 2^c of the frame by a bracket 11, which extends inwardly from such side member. On the inner and upper portion of the bracket is pivotally mounted the master arm 12, such mounting being preferable at the median portion of the arm. One end of the arm, which may be referred to as the normally lower end thereof when the door is closed, is pivotally connected to the door 1 near the lateral edge of the door and substantially at the median portion between the normally upper and lower edges 10 of the door. Such pivotal connection is preferably made to an inwardly extending flange 13^a of a side rail 13, which is secured in a normally vertical position to the inner side of the door.

On the outer side, that is, the door side, of the bracket 11, is also pivotally mounted one end of a positioning link 14, which consists of a pair of longitudinally adjustable link members 14^a and 14^b. The extended end of the link member 14^a is pivotally connected to the bracket 11 on an axis located downwardly from and forwardly of the axis of the pivotal mounting of the master arm 12 on the bracket. The link members are adjustably connected together by means of a pair of bolts 15 which extend through longitudinal slots 14^c in one of the link members.

The opposite end of the link 14 is pivotally connected to the extended end of an arm or bracket 16. The opposite or inner portion of the arm or bracket 16 is secured to the flange 13^a of the rail 13, near the end thereof adjacent the normally lower edge of the door. The arm or bracket 16, extending inwardly as it does from the inner surface of the door, reduces the extent of travel of the door above the height of the upper end of the frame 2 and thus enables the apparatus to be used on garages having relatively low roofs or ceilings.

To facilitate free swinging of the door 1, the portion 11^a of the bracket 11, upon which the master arm 12 is mounted, is offset towards the door. Also the end portion of the link member 14^a, which is pivotally mounted on the bracket 11, is also offset towards the bracket so as to provide sufficient clearance for the movement of the door.

In order to facilitate the shifting of the door from the closed to the open position, and vice versa, a coil spring 17 is provided at each of the lateral sides of the door. The spring 17 connects the other end portion 12^a, that is, the normally upper end portion of the master arm, to

the inner side of the lower portion of the side member 2^c of the frame, as shown in Figs. 1 and 2. The connection of the upper end of the spring to the master arm is through a kicker plate 18. One end of the kicker plate is pivotally connected by a bolt 19 through one of the plurality of holes 12^b in said opposite end of the master arm. The spring is attached through a hole 18^a in the opposite end of the kicker plate. This kicker plate is adjustably positioned with respect to the master arm by means of a bolt 20, which extends through a slot 18^b and normally engages loosely the inner edge of the master arm 12. The slot 18^b extends angularly with respect to the line connecting the holes at the opposite ends of the kicker plate. With this construction the end of the spring may be operatively connected to the end portion of the master arm at various distances inwardly from the inner edge of the latter. Such adjustment may be made by securing the bolt 20 in various positions within the slot.

The lower end of the spring 17 may be connected in any suitable manner, such as by means of a strap 21, to the lower portion of the side member 2^c of the frame.

A stop 22 may also be provided on the jamb or side member of the frame, as indicated in Fig. 1.

I wish it to be understood that I do not desire to be limited to the exact details of construction shown and described, for obvious modifications will occur to a person skilled in the art.

I claim:

1. A mechanism of the type described for pivotally supporting an overhead door on a door frame, comprising: a bracket for mounting to the door frame; a master arm pivotally mounted intermediate the ends thereof to said bracket; means for pivotally connecting one end of said arm to the door adjacent one edge thereof; said master arm being movable to position an intermediate portion of the door within the door frame; a link of adjustable length; a pivot pin pivotally connecting a first end of said link to said bracket at a point fixedly spaced from the pivotal mounting of said arm to said bracket; means for pivotally connecting the second end of said link to the normally inner side of the door at a point downwardly spaced from the pivotal connection between said arm and door, said link controlling the angular position of said door as it moves with and relative to said arm between open and closed positions; means for adjusting the length of said link while the aforesaid intermediate portion of the door is within the door frame to thereby cause the door to lie in a vertical plane within the door frame; and means including a tension spring for interconnecting the free end of said arm and the lower portion of the door frame for applying an upwardly directed force to the door.

2. A mechanism of the type described for pivotally supporting an overhead door on a door frame, comprising: a bracket for mounting to

the door frame; a master arm pivotally mounted intermediate the ends thereof to said bracket; means for pivotally connecting one end of said arm to the door adjacent one edge thereof; said master arm being movable to position an intermediate portion of the door within the door frame; a link; a pivot pin pivotally connecting a first end of said link to said bracket at a point fixedly spaced from the pivotal mounting of said arm to said bracket; a member for attachment to the normally inner side of the door at a point downwardly displaced from the pivotal connection between said arm and door; means for pivotally connecting the second end of said link to said member; said link and said member controlling the angular position of said door as it moves with and relative to said arm between open and closed positions; means for adjusting the distance from said pivot pin to the point of connection of said member to the door while the aforesaid intermediate portion of the door is within the door frame to thereby cause the door to lie in a vertical plane within the door frame; and means including a tension spring for interconnecting the free end of said arm and the lower portion of the frame for applying an upwardly directed force to the door.

3. A mechanism of the type described for pivotally supporting an overhead door on a door frame, comprising: a bracket for mounting to the frame; a master arm pivotally mounted to said bracket; means for pivotally connecting one end of said arm to the door adjacent one edge thereof; said master arm being movable to position an intermediate portion of the door within the door frame; a link; a pivot pin pivotally connecting a first end of said link to said bracket at a point fixedly spaced below the pivotal mounting of said arm to said bracket; a member for pivotally connecting the second end of said link to the normally inner side of the door at a point downwardly spaced from the pivotal connection between said arm and door, said link and said member controlling the angular position of said door as it moves with and relative to said arm between open and closed positions; means for adjusting the length of said link while the aforesaid intermediate portion of the door is within the door frame to thereby cause the door to lie in a vertical plane within the door frame.
